UNITED STATES PATENT OFFICE.

HORACE D. BALL, JOHN I. FLOYD, AND LEONARD S. CARR, OF BELOIT, WISCONSIN.

DIRECTION-INDICATOR.

1,126,684.

Specification of Letters Patent.

Patented Feb. 2, 1915.

Application filed May 18, 1914. Serial No. 839,342.

To all whom it may concern:

Be it known that we, HORACE D. BALL, JOHN I. FLOYD, and LEONARD S. CARR, citizens of the United States, residing at Beloit, in the county of Rock and State of Wisconsin, have invented certain new and useful Improvements in Direction-Indicators, of which the following is a specification.

This invention relates to devices for indicating directions and more particularly to those for use with motor vehicles, for the purpose of signifying by a display character, the direction in which the operative intends to turn the vehicle.

One of the primary objects of our invention is to provide a direction indicator of improved design and construction which will have few movable parts and which will be cheap to manufacture.

Another object of our invention is to provide a pair of indicating characters arranged in a novel manner, movable to indicating and non-indicating positions, and which will permit a relatively large direction representation.

A further object of our invention is to provide in a direction indicator, a simple mechanism for operating the indicating characters, whereby many-movable parts which complicate the manner and operation of the device, are avoided.

A further object of our invention is to provide a pair of indicating characters, electro-magnets, and means operable between the indicating characters and electro-magnets whereby each magnet may be rendered operative for moving a certain character into a display position.

Referring to the drawings: Figure 1 is a plan sectional view taken on the line 1—1 of Fig. 2 of our improved direction indicator. Fig. 2 is a vertical sectional view taken on the line 2—2 of Fig. 1. Fig. 3 is a vertical sectional view taken on the line 3—3 of Fig. 1. Fig. 4 is a detail view taken on the section line 4—4 of Fig. 3. Fig. 5 is a plan sectional view taken on the line 5—5 of Fig. 2, showing the indicating characters in a non-indicating position. Fig. 6 is a face view of our improved direction indicator, showing the character R moved to a direction indicating position. Fig. 7 is a similar view but with the character L in direction indicating position; and Fig. 8 is a view in

elevation of the rear end of a motor vehicle, showing the application of our improved direction indicator thereto.

On the drawings illustrating our invention we have shown a rectangular shaped base 9 upon which our improved direction indicating mechanism is mounted, which base may be provided with any suitable or preferred fastening means whereby the device may be attached to a motor vehicle, either to the front or rear thereof as is customary with such devices.

A casing 11 rectangular in shape, surrounding the base 9 and being detachably connected thereto by screw-bolts 12, is formed with a top 13 spaced from the base 9 and provided with a circular raised portion 14 having a depressed annular seat 15 and a face-opening 16, whereby a face to the casing is provided.

A relatively thin and non-transparent face-member 17 is mounted upon the annular seat portion 15, covering the opening 16, and is provided with a rectangular opening 18 which is arranged to occupy substantially the greater right-hand portion of the face 17 as viewed in Figs. 5, 6, and 7.

A circular glass face 19 is mounted upon the annular seat 15, surmounting the non-transparent face member 17, and is retained in position by means of an annular rim 21 which is shaped to engage the periphery of the glass face and also the periphery of the raised circular portion 14. The annular rim 21 may be detachably connected to the casing in any suitable or preferred manner, it being herein shown connected to the raised face portion 14 by means of screw-bolts 22.

A yoke-shaped bearing standard is formed centrally upon the base within the casing, providing vertically aligned upper and lower bearing portions 23 and 24 respectively, the latter providing a needle point bearing and the former having a sleeve bearing 25 screw-threaded to the bearing arm 23 so as to be adjustable axially. The sleeve bearing is provided with a lock-nut 26 for locking the bearing in a set position. A pivot-shaft or pintle 27 is journaled in the sleeve bearing 25, and has its lower end mounted in the needle point bearing 24 and its upper end extended above the sleeve bearing to provide means upon which the direction indicating

characters may be mounted in operative relation with the sight opening 18. This shaft is provided with a fixed annular flange 20, against which the lower end of the sleeve 25 abuts, for the purpose of maintaining the shaft seated in its end bearing and for holding it from actual displacement. It will be noticed from the drawings that the pintle 27 is in vertical alinement with the sight opening 18, the purpose of this being to permit the peculiarly arranged indicating characters to be properly positioned and moved relatively to said sight opening.

The characters L and R for signifying the directions "left" and "right," respectively, are combined into one character or symbol 30 in such a manner that the vertical strokes of each letter are one and the same, the character L being reversed relatively to the character R. The vertical stroke of the combined characters designated by the reference character 28 is fixedly attached to the pintle 27 so that by rotary movement of the pintle both the characters L and R may be alternatively moved into position beneath the sight opening 18 and be visible therethrough to designate the direction which they represent. In Fig. 5 the indicating character is shown in a neutral or non-indicating position; in Fig. 6 it is shown with the R character moved into alinement with the sight opening to signify "right"; and in Fig. 7 it is shown with the L character moved to its operative position to signify "left."

The means for imparting rotary movement to the pintle comprises a pair of electro-magnets 29 and 31 positioned on diametrically opposite sides of pintle 27 and mounted upon lugs 32 formed with the base 9, a bar 33 mounted reciprocable in a horizontal plane in lugs 34 interposed between the electro-magnets, the bar being provided at its ends with contact faces 35 which are operable upon by the magnets to move the bar longitudinally in either of opposite directions, and a gear and rack connection 36 between the pintle 27 and the bar 33. It will be manifest that by movement of the rack-bar 33 longitudinally by either of the electro-magnets, the pintle will be rotated accordingly, and the direction indicating character will be moved relatively to the sight opening to locate either of its characters in a readable position. A flat spiral spring 37 surrounding the pintle 27, having one end fixedly attached thereto and its opposite end attached to the yoke-bearing post, serves as a means to normally maintain the pintle in a neutral position wherein the direction indicating characters are in non-indicating position as shown in Fig. 5, and also as means for returning the pintle to its neutral position after the rod 33 has been released by either of the magnets.

A partition member 38 attached to the underside of the top casing 13 and underlying the entire circular face portion 14 and the direction indicating character, is provided with a central aperture 39 through which the pintle 27 extends. This partition is translucent so that the mechanism for operating the pintle is veiled from sight through the opening 18, while the outline of the direction indicating character 75 illuminated by an artificial light in the form of an electric bulb 41 located within the casing is clearly discernible therethrough.

The terminal wires of the electro-magnets designated generally by the reference character 42, may be suitably arranged and connected with switch means (not shown) located within control of the operative of the vehicle so that by closing the circuit of either electro-magnet, such magnet may be rendered operative to move one of the characters into direction indicating position. By connecting the electro-magnet terminals for operating like characters at the front and rear of the vehicle, in the same circuit, the like characters of both indicating devices may be operated simultaneously.

It will be seen that with the above described means for indicating directions a relatively large size direction symbol may be employed in a comparatively small-faced indicating device, and that the simple and novel mechanism for operating the indicating characters permits the device to be housed in a small and convenient casing so as to occupy but little space on the vehicle.

It is believed that our invention and its mode of operation will be readily understood from the foregoing without further description; and other modified forms may be made without departing from the spirit and scope of our invention as set forth in the following claims.

We claim as our invention:

1. In a direction indicator, the combination of a casing having a display opening therein, a symbol arranged within the casing for signifying different directions, comprising characters L and R arranged with their vertical strokes in common, and means for moving said symbol relatively to the display opening in such manner that either of said characters may be read individually through the said display opening.

2. In a direction indicator, the combination of a casing having a display opening therein, a symbol arranged within the casing for signifying different directions, comprising characters L and R combined into a single character, and means for moving said symbol relatively to the display opening in such manner that either of the said characters L or R may be read individually through the said display opening.

3. In a direction indicator, the combination

tion of a casing having a display opening therein, and a symbol for signifying different directions, comprising characters L and R arranged with their vertical strokes in common, the symbol being pivotally mounted at a centrally disposed point thereon so that by movement of the symbol upon its pivot its characters L and R may be in-

dividually moved into position readable through the display opening.
